CIGARETTE EXTINGUISHER

Filed Aug. 9, 1929

George R. Burton Inventor

By *Marion Marion* Attorneys

UNITED STATES PATENT OFFICE

GEORGE R. BURTON, OF MONTREAL, QUEBEC, CANADA

CIGARETTE EXTINGUISHER

Application filed August 9, 1929. Serial No. 384,568.

The present invention relates to improvements in extinguishing devices, particularly adapted for extinguishing cigarettes, cigars and the like.

- 5 An important object of the invention is the provision of a device adapted to be associated with an ash tray and arranged for reciprocating movement to extinguish cigarettes and the like properly positioned on the tray.
- 10 A further object of the invention is the provision of an extinguishing device of the above character which may also be rotated to discard or displace the cigarette after extinction to an out of the way position.

- 15 Another object of the invention is the provision of an extinguishing device which may be simply manipulated with one hand.

- 20 Still another object of the invention is the provision of an extinguishing device mounted so as to normally assume an elevated position out of contact with the cigarette.

- 25 Other objects and advantages of the invention will become apparent as the description progresses.

- 30 In the accompanying drawings forming a part of this specification and in which like reference characters are employed to designate corresponding parts throughout the same:

- 35 Figure 1 is a perspective view of the preferred form of the invention.

Figure 2 is a fragmentary vertical section through the same in its elevated position prior to extinguishing movement.

- 40 Figure 3 is a similar view showing the device actuated to an extinguishing position.

Figure 4 is a fragmentary top plan view illustrating the action of the extinguishing member.

- 45 Figure 5 is a fragmentary vertical section through a modified form of construction showing the extinguishing member in its elevated position.

Figure 6 is a similar enlarged view showing the member in a partially lowered position, and

Figure 7 is a fragmentary vertical section showing a modified mounting connection.

- 50 Referring to the preferred form of the invention, illustrated in Figures 1 to 4, inclu-

sive, the numeral 10 generally indicates a conventional form of ash tray commonly employed as a receiver for cigarettes and cigars, in the present instance including a flat bottom 11 and an annular marginal rim 12.

55 Rigidly attached to the tray 10, preferably to the centre of the bottom portion 11, is an upright guide post 13, preferably formed with a shoulder 14 adjacent the lower end with an extension of the extremity projecting through the bottom to retain the same rigidly in a vertical position. On the upper end of the post 13 is mounted a detachable collar 15 threadedly connected with the post or otherwise attached thereto.

60 Slidably associated with the guide post 13 for reciprocating operative movement is an assembled stamping member, generally indicated at 16, embodying an upper cylinder 17 and a lower stamping element 18.

65 The cylinder 17, having the form of an elongated sleeve, is enclosed at the top end, as designated at 19, and is formed to readily slide over the guide post and collar 15 fixed thereon. The lower open end of the cylinder 70 is counterbored or threaded for connection with the lower stamping element 18.

75 The element 18 is formed to provide a horizontally extending base plate 20, preferably of circular form, flat on its lower side 80 and provided with a frusto-conical boss 21 at its upper side. The stamping element 18 is formed with a central through bore disposed transversely therethrough, through which is extended the guide post 13, both of 85 which are preferably circular in cross section and designed to form a relatively snug sliding fit.

80 Mounted between the upper closed end 19 of the cylinder and the collar 15 attached to the guide post is a spiral compression spring 22 constructed to normally maintain the assembled stamping member in an elevated position, the upward movement of the member being restricted by the collar 15, the exterior 85 diameter of which is greater than the diameter of the bore in the element 17.

90 In use, the assembled stamping member will normally assume an elevated position with respect to the ash tray, that is, the 100

stamping plate 20 will be disposed substantially above the bottom of the tray to permit convenient insertion of a cigarette. To extinguish a lighted cigarette or cigar, the 5 article is placed so that the lighted end will be arranged on the tray bottom below the stamping plate in its normal elevated position. The reciprocating stamping assembly is then forced downwardly against the compression of the spring 22 onto the cigarette, 10 crushing the lighted end thereof so as to completely extinguish the fire. The reciprocable stamping assembly is then rapidly rotated so as to displace the cigarette from the 15 central portion of the tray to the side margin for a repeated extinguishing operation.

In the modified construction shown in Figures 5 and 6, the guide post indicated at 22' is formed to provide a twisted or threaded 20 spiral engaging a screw 23 threaded transversely through the boss of the stamping member 18 so that the stamping assembly will automatically rotate as it is pushed downwardly so that the cigarette displacing 25 action is concurrent with the vertical extinguishing displacement so as to automatically discard the extinguished cigarette or cigar. This form of the invention is also shown applied to an ash tray formed of glass or similar material, indicated at 24, the lower end 30 of the guide post being threaded through a pair of flanges 25 secured in opposed positions to the bottom of the tray.

In Figure 7 is illustrated a modified connection of the guide post, indicated at 26, with a glass tray, indicated at 27. In this construction, the lower end of the post is provided with an interiorly threaded bore having connection with a screw 28 formed 40 with an enlarged beveled head extending in a countersunk opening in the bottom of the tray.

Thus, the present invention provides an extinguishing device of relatively simple construction and operation designed so that the cigarette or cigar to be extinguished may be placed in an extinguishing position and the reciprocating extinguishing member operatively actuated by using only one hand, enabling use while the operator is engaged in playing cards or is otherwise employing the other hand.

It is to be understood that the form of my invention herein shown and described is to 55 be taken as a preferred example of the same, and that various changes as to the shape, size, and arrangement of parts may be resorted to without departing from the spirit of the invention or the scope of the subjoined claims.

Having thus described my invention, I 60 claim:

1. A cigarette extinguishing device comprising an upright guide post attached to a supporting member, a horizontally extending stamping plate disposed for vertical slid-

ing movement on the post, and a cylinder attached to the upper portion of the stamping plate slidable over the post for operative movement of the stamping plate.

2. A cigarette extinguishing device comprising an upright guide post, a horizontally extending stamping plate provided with a central through bore arranged for reciprocating and rotary movement on the post, a cylinder having its lower extremity attached 70 to the upper portion of the stamping plate for vertically and rotatably actuating the plate, and spring means mounted in the cylinder arranged to normally elevate the cylinder and stamping plate.

3. A cigarette extinguishing device comprising an upright guide post, a reciprocating stamping member associated with the said guide post, and means whereby the stamping member will be rotated during 80 reciprocating action thereof.

4. A device of the character described comprising a tray, a guide post attached to the tray, a flat stamping plate slidably associated with the post and arranged exteriorly thereof, and means normally resiliently urging the said plate to a predetermined elevated position.

5. A device of the character described comprising a tray, a guide post attached to and 90 projecting upwardly from the bottom of the tray, a stamping plate slidably connected with the post, and means normally urging the said stamping plate to an elevated position.

6. A device of the character described comprising a tray, a guide post projecting upwardly from the bottom of the tray centrally thereof, a stamping plate slidably associated with the guide post, means for adjusting the position of the stamping plate, and means 100 resiliently supporting the said plate in an elevated position.

In witness whereof I have hereunto set my hand.

GEORGE R. BURTON.
